UNITED STATES PATENT OFFICE

ARTHUR G. LEAKE, OF BRIDGEPORT, CONNECTICUT

DESIGN FOR A BOOK END

Application filed June 17, 1931. Serial No. 40,242. Term of patent 3½ years.

To all whom it may concern:

Be it known that I, ARTHUR G. LEAKE, a citizen of the United States, residing at Bridgeport, county of Fairfield, State of Connecticut, have invented a new, original, and ornamental Design for a Book End, of which the following is a specification, reference being had to the accompanying drawings, forming part thereof.

Fig. 1 is a perspective view of a book end looking from one side, showing my new design, and

Fig. 2 is a perspective view thereof looking from the front.

I claim:

The ornamental design for a book end, substantially as shown.

ARTHUR G. LEAKE.
